UNITED STATES PATENT OFFICE.

ELLES E. HARTMAN, OF EAST JORDAN, MICHIGAN.

VENDING MACHINE.

Application filed October 23, 1920. Serial No. 418,926.

To all whom it may concern:

Be it known that I, ELLES E. HARTMAN, a citizen of Hungary, residing at East Jordan, county of Charlevoix, State of Michigan, have invented certain new and useful Improvements in Vending Machines, of which the following is a full, clear, and exact description.

This invention relates to improvements in coin controlled apparatus for vending merchandise, such as candies, chewing-gum or other articles. One of the objects of the invention is to provide an apparatus consisting of few parts which will be positive in operation and compact. The movable parts of my improved apparatus are dependent upon a coin, that is to say, a coin constitutes the element which operates the delivering elements when dropped into position within a suitable actuator. My improved vending apparatus is arranged for double actuation; that is to say, I employ two containers from either one of which articles can be removed. Other features of improvement will herein-after appear.

I will now describe my invention in detail, the novel features of which I will finally claim, reference being had to the accompanying drawings, wherein:

Fig. 1 illustrates a front elevation of my improved apparatus, partly in section;

Fig. 2 is a top plan view thereof;

Figs. 3 and 4 are detail views, illustrating the action of the operating parts of the apparatus;

Fig. 5 is a fragmentary sectional view, the section being taken on a line 5-5 in Fig. 6;

Fig. 6 is a sectional plan view, the section being taken on a line 6-6 in Fig. 1;

Fig. 7 is an enlarged fragmentary sectional view, the section being taken on a line 7-7 in Fig. 6;

Fig. 8 is an enlarged fragmentary sectional detail view, the section being taken on a line 8-8 in Fig. 7; and

Fig. 9 is a detail plan view of a portion of the top plate of the casing, illustrating the agitating fingers and also the opening 50 through said plates.

As herein embodied, my improved coin controlled apparatus consists of (in this instance) two containers 9 and 10, preferably of glass, designed to contain candies, chewing gum or the like, indicated by 11. In this instance, I have illustrated the said

articles as in the form of small spheres. The articles within each container will drop one by one into a chute 12, adjacent thereto. The chutes 12 merge into a common receptacle 13^a into which a hand can be inserted to withdraw the articles which have dropped thereinto. The dropping of the articles 11 into the receptacle 13^a is controlled by means of slides or gates 13, 14, 15, and 16, arranged in pairs, there being a pair under each container. The slides 13 and 14 are slidably mounted on a block 17, carried by casing 19, and the slides 15 and 16 are slidably mounted on a similar block 18.

The upper slides 13 and 15 each carry a shoe 20 which projects downwardly, and each under slide 14 and 16 carries an upwardly projecting shoe 21, said shoes being arranged to be contacted by a coin carried by a rotatable bar or actuator 22. The coins (one of which is indicated by 23), will be dropped into a slot 24 carried by said bar, through a coin chute 25. Unless there be a coin within the slot 24, the bar 22 can be freely rotated to the right or left by means of a hand-wheel 26, and slides or gates 13, 14, 15 and 16 will not be actuated. When a coin is dropped into the chute 25, it will drop into slot 24. If the handle 26 is rotated to the right or left, bar or actuator 22 will be likewise rotated. When bar 22 is rotated, to the left, for instance (see Figs. 3 and 4), the coin 23 will first contact with shoe 20 and by a continued movement said slide or gate 13 will be moved toward the left, causing opening 27 therein (Fig. 5) to move to the left and also causing the agitator fingers 28 and 29 carried by slide or gate 13 to move to the left, whereby the lowermost article 11^a will drop through opening 27 into the space 30 between gates 13 and 14 (see dotted lines Fig. 5). A continued rotation of bar or actuators 22 will cause the coin to contact with shoe 21 and move it, and gate 14, toward the left, whereby opening 31, in slide 14, will align with the adjacent chute 12 and the article will drop into the receptacle 13^a. To form a substantially enclosed space 30, I provide the under gate 14 with a guard 32 and the block 17 with projecting sides 33, all of which act to retain the article dropped between the upper and lower slides. Should bar or actuator 22 be rotated toward the right, slides or gates 15 and 16 would be actuated and the operation described in con-

nection with gates 13 and 14 would result. Parts coordinated with slides 15 and 16 which are the same as parts coordinated with gates 13 and 14 have been given the same numeral indications. The fingers 28 and 29 act to agitate the articles within the containers, when they are moved; hence, prevent said articles from bridging the openings 34, in the top 35 of the casing 19, said openings alining with the openings 27 in the upper gates 13 and 15. The top plate 35 is provided with slots 36 (Fig. 5) for fingers 28 to operate in. The openings 34 will be large enough for fingers 29 to work in. The fingers 29 will act to restrict said openings 34, when in normal position, in order to prevent articles within the containers 9 and 10 from dropping through (see Fig. 9).

The slides or gates 13 and 15 are connected by a spring 37 and slides 14 and 16 by a similar spring 38. These springs act to return the slides to normal position after having been operated. After bar or actuator 22 has been turned completely over or rotated one half of a revolution, the coin 23 will drop onto a chute 39 and from thence into a suitable receptacle 40 (see Fig. 7).

The bar 22 carries a pin 41 which, when the bar has been rotated one half a revolution, will strike a stop 42, thereby limiting the movement of said bar 22. The pin also coacts with a yieldable latch 42^a which acts to position the slot 24 in said bar or actuator 22 in alinement with chute 25. The bar or actuator 22 is also provided with a coil spring 43 which acts to return the bar after it has been released subsequently to the operation thereof to actuate the slides. When the bar is rotated, to the right or left, spring 43 will be wound up or placed under tension; hence, when said bar is released, the spring will return the bar to normal position.

One of the features of the invention is that bar or actuator 22 has to be turned completely over in order to cause the coin carried thereby to actuate both slides; if the bar is turned but one quarter way, it cannot be turned back, as the coin would catch under shoe 20 (see Fig. 4). Owing to the springs 37 and 38, the tension of which will be relatively stiff, a paper, tin or lead disk would not operate the device as disks, made of such material would bend before the slides or gates could be actuated.

It will be apparent that the diameter of rod or actuator 22 is less than the diameter of the coin 23; hence the coin will project beyond the peripheral surface of the actuator sufficiently to engage the shoes on the gates or slides.

Having described my invention, what I claim and desire to secure by Letters Patent is:

65 1. In a coin controlled apparatus, a con-

tainer having an outlet, gates adjacent said outlet, each gate having an opening normally out of alinement with the outlet from said container, and actuating means dependent upon the presence of a coin therein to actuate said gates, one at a time, to cause the openings therein to be positioned relative to the outlet from said container for the passage of an article from said container, the coin forming the connection between said gates and actuating means.

2. In a coin controlled apparatus, a container having an outlet, a chute for the passage of articles from within the container, a gate adjacent said outlet and having an opening normally out of alinement therewith, a gate adjacent said chute having an opening normally out of alinement therewith, said gates being separated sufficiently to form a temporary receptacle for articles passing through said gates, and an actuator arranged to receive a coin and to maintain same in such position as to cause said coin when the actuator is operated to actuate firstly the gate adjacent said outlet to cause the opening therein to aline with said outlet and then the gate adjacent the chute to cause the opening therein to aline with said chute.

3. In a coin controlled apparatus, a container having an outlet, a chute for the passage of articles from within the container, a gate adjacent said outlet and having an opening normally out of alinement therewith, a gate adjacent said chute having an opening normally out of alinement therewith, said gates being separated sufficiently to form a temporary receptacle for articles passing through said gates, an actuator arranged to receive a coin and to maintain same in such position as to cause said coin, when the actuator is operated, to actuate firstly the gate adjacent said outlet to cause the opening therein to aline with said outlet and then the gate adjacent the chute to cause the opening therein to aline with said chute, and means to return the gates and the actuator to normal position after each actuation thereof.

4. In a coin controlled apparatus, a container having an outlet, a chute for the passage of articles from within the container, a gate adjacent said outlet and having an opening normally out of alinement therewith, a gate adjacent said chute having an opening normally out of alinement therewith, said gates being separated sufficiently to form a temporary receptacle for articles passing through said gates, a rotatable actuator arranged to receive a coin and to maintain same in such position as to cause said coin, when the actuator is operated, to actuate firstly the gate adjacent said outlet to cause the opening therein to aline with said outlet and then the gate adjacent the chute to cause the opening therein to aline with said chute.

chute, and means to return the gates and the actuator to normal position after each actuation thereof.

5. In a coin controlled apparatus, a container having an outlet, a chute for the passage of articles from within the container, a gate adjacent said outlet and having an opening normally out of alignment therewith, a gate adjacent said chute having an opening normally out of alignment therewith, said gates being separated sufficiently to form a temporary receptacle for articles passing through said gates, an actuator arranged to receive a coin and to maintain 10 same in such position as to cause said coin, when the actuator is operated, to actuate firstly the gate adjacent said outlet to cause the opening therein to align with said outlet and then the gate adjacent the chute to cause 15 the opening therein to align with said chute, and means to prevent the actuator from being returned to normal position after it has been rotated to a predetermined extent.

6. In a coin controlled apparatus, a container having an outlet, a gate adjacent thereto having an opening normally out of alignment with said outlet, a second gate to form a temporary receptacle, said second gate having an opening therethrough, a chute adjacent the second gate but out of alignment with the opening therein, a rotatable actuator adjacent said gates having a slot to receive a coin, the diameter of the actuator being less than the diameter of the 20 coin, whereby a coin will project beyond the peripheral surface of the actuator, and means associated with each gate arranged to be engaged by a coin when the actuator is operated whereby said gates will be actuated to cause the openings therein to align with the said outlet and said chute.

7. In a coin controlled apparatus, a container having an outlet, a gate adjacent thereto having an opening normally out of alignment with said outlet, a second gate spaced from the first gate to form a temporary receptacle, said second gate having an opening therethrough, a chute adjacent the second gate but out of alignment with the opening therein, a rotatable actuator adjacent said gates having a slot to receive a coin, the diameter of the actuator being less than the diameter of the coin, whereby a coin will project beyond the peripheral surface of the actuator means associated with each gate arranged to be engaged by a coin when the actuator is operated whereby said gates will be actuated to cause the openings therein to align with the said outlet and said chute, and a spring to return the actuator to normal position after the actuation thereof.

8. In a coin controlled apparatus, a container having an outlet, a gate adjacent thereto having an opening normally out of

alignment with said outlet, a second gate spaced from the first gate to form a temporary receptacle, said second gate having an opening therethrough, a chute adjacent the second gate but out of alignment with the opening therein, a rotatable actuator adjacent said gates having a slot to receive a coin, the diameter of the actuator being less than the diameter of the coin, whereby a coin will project beyond the peripheral surface of the actuator to actuate said gates, a shoe carried by the first gate, a shoe carried by the second gate, and means to rotate the actuator to cause the coin therein to contact firstly with the shoe on the first gate and 75 actuate said gate, and secondly with the shoe on the second gate to actuate the second gate, to cause the openings in said gates to permit of the passage of articles from said container. 80

9. In a coin controlled apparatus, a container having an outlet, a gate adjacent thereto having an opening normally out of alignment with said outlet, a second gate spaced from the first gate to form a temporary receptacle, said second gate having an opening therethrough, a chute adjacent the second gate but out of alignment with the opening therein, a rotatable actuator adjacent said gates having a slot to receive a coin, the diameter of the actuator being less than the diameter of the coin, whereby a coin will project beyond the peripheral surface of the actuator to actuate said gates, a shoe carried by the first gate, a shoe carried by the second gate, and means to rotate the actuator to cause the coin therein to contact firstly with the shoe on the first gate and 90 actuate said gate, and secondly with the shoe on the second gate to actuate the second gate, to cause the openings in said gates to permit of the passage of articles from said container. 95

10. In a coin controlled apparatus, a container having an outlet, a gate adjacent thereto having an opening normally out of alignment with said outlet, a second gate spaced from the first gate to form a temporary receptacle, said second gate having an opening therethrough, a chute adjacent the second gate but out of alignment with the opening therein, a rotatable actuator adjacent said gates having a slot to receive a coin, the diameter of the actuator being less than the diameter of the coin, whereby a coin will project beyond the peripheral surface of the actuator to actuate said gates, a shoe carried by the first gate, a shoe carried by the second gate, means to rotate the actuator to cause the coin therein to contact 100 110 120 125 130

firstly with the shoe on the first gate and actuate said gate, and secondly with the shoe on the second gate to actuate the second gate, to cause the openings in said gates to permit of the passage of articles from said container, the shoe on the first gate being arranged to act as a stop and engage the coin carried by the actuator should the motion of the actuator be reversed after it has been moved to a predetermined extent in operative direction, and means to arrest the rotation of the actuator after it has been turned one half of a revolution.

11. In a coin controlled apparatus, a container having an outlet, a gate adjacent thereto having an opening normally out of alignment with said outlet, a second gate spaced from the first gate to form a temporary receptacle, said second gate having an opening therethrough, a chute adjacent the second gate but out of alignment with the opening therein, a rotatable actuator adjacent said gates having a slot to receive a coin, the diameter of the actuator being less than the diameter of the coin, whereby a coin will project beyond the peripheral surface of the actuator to actuate said gates, a shoe carried by the first gate, a shoe carried by the second gate, means to rotate the actuator to cause the coin therein to contact firstly with the shoe on the first gate and actuate said gate, and secondly with the shoe on the second gate to actuate the second gate, to cause the openings in said gates to permit of the passage of articles from said container, the shoe on the first gate being arranged to act as a stop and engage the coin carried by the actuator should the motion of the actuator be reversed after it has been moved to a predetermined extent in operative direction, means to arrest the rotation of the actuator after it has been turned one half of a revolution.

lution, and a spring to return the actuator to normal position after it has been released. 45

12. In a coin controlled apparatus, a container having an outlet, a gate adjacent thereto having an opening normally out of alignment with said outlet, a second gate spaced from the first gate to form a temporary receptacle, said second gate having an opening therethrough, a chute adjacent the second gate but out of alignment with the opening therein, a rotatable actuator adjacent said gates having a slot to receive a coin, the diameter of the actuator being less than the diameter of the coin, whereby a coin will project beyond the peripheral surface of the actuator to actuate said gates, a shoe carried by the first gate, a shoe carried by the second gate, means to rotate the actuator to cause the coin therein to contact firstly with the shoe on the first gate and actuate said gate, and secondly with the shoe on the second gate to actuate the second gate, to cause the openings in said gates to permit of the passage of articles from said container, the shoe on the first gate being arranged to act as a stop and engage the coin carried by the actuator should the motion of the actuator be reversed after it has been moved to a predetermined extent in operative direction, means to arrest the rotation of the actuator after it has been turned one half of a revolution, a spring to return the actuator to normal position after it has been released, and a latch to position the actuator in its normal position after it has been returned to said normal position by said spring. 65 70 75 80
